UNITED STATES PATENT OFFICE.

CHARLES N. BLACK, OF NEW HAVEN, CONNECTICUT.

AUTOMATIC APPARATUS FOR PROTECTING COMPOUND-WOUND DYNAMOS.

SPECIFICATION forming part of Letters Patent No. 650,704, dated May 29, 1900.

Application filed August 15, 1898. Serial No. 688,582. (No model.)

To all whom it may concern:

Be it known that I, CHARLES N. BLACK, of New Haven, in the county of New Haven and State of Connecticut, have invented a new Improvement in Automatic Apparatus for the Protection of Compound-Wound Dynamos; and I do hereby declare the following, when taken in connection with the accompanying drawings and the letters of reference marked thereon, to be a full, clear, and exact description of the same, and which said drawings constitute part of this specification, and represent, in—

Figures 1, 2, 3, 4, and 5, diagrammatic representations of different forms which my invention may assume.

My invention relates to an improved automatic apparatus for protecting a compound-wound dynamo against the exigencies of use, such as an overload or short circuit, the object being to provide dynamos of the character described with simple, reliable, and effective means for their protection.

Heretofore compound-wound dynamos have generally been protected by means of circuit-breakers which break the main or working circuit of the dynamo. Owing to the fact that, however constructed, these circuit-breakers are in the nature of their operation constantly subjected to the disintegrating action of the electric arc or "flashing" when in operation, they require constant attention and repair and are not infrequently destroyed. They are generally expensive in their initial construction and expensive to maintain and are on these accounts objectionable, and for the further reason that if they fail to operate the machine which they are designed to protect may sustain serious damage.

With the ends above stated in view my invention consists in an automatic apparatus for short-circuiting the series windings of a compound-wound dynamo.

My invention further consists in an automatic apparatus for short-circuiting the series windings of a compound-wound dynamo and for opening the equalizer connection when two or more of such machines are connected for operation in parallel.

My invention further consists in an automatic apparatus for short-circuiting the series windings of a compound-wound dynamo for

opening the equalizer connection when two or more of such machines are connected for operation in parallel and for cutting out the series windings without breaking the main or working circuit.

My invention further consists in an automatic apparatus having certain details of construction, as will be hereinafter described, and pointed out in the claims.

For the purpose of illustrating my invention I have shown it as applied to the protection of a compound-wound dynamo connected in parallel with other corresponding machines, as indicated, by the employment of an equalizer connection.

In carrying out my invention as shown in Fig. 1 of the drawings I employ a positive bus-bar or conductor A, an equalizer bus-bar or conductor B, and a negative bus-bar or conductor C. The said positive bus-bar A is connected in the usual manner by a conductor D with the series windings E of a compound-wound dynamo, which is, so to speak, "diagrammatically" represented. The said equalizer bus-bar B is connected by a conductor F with a contact-piece or clip G, which may be of any approved construction and which is normally engaged by and in electrical contact with a movable conductor H, which, as shown, consists of a wide flat copper blade pivotally mounted at one end upon a pivot H', which supports the blade in the bracket I, with which it is electrically connected. The said bracket I is itself connected by a conductor J to the positive commutator-brush K, which is also connected to the other end of the series windings E. The negative bus-bar C is connected by a conductor L to the coil M of an electromagnetic device, also comprising a yoke M', the leg m of which the coil encircles. The other leg m' of the magnet-yoke has attached to it a spring M², the lower end of which carries an armature M³, which is located adjacent to the leg m of the magnet-yoke M'. The other end of the coil M is connected by a conductor N to the negative commutator-brush O, which rides upon the commutator P, also engaged by the positive commutator-brush K, before mentioned. The said brush O is connected by a conductor Q with one end of the shunt-windings R, the other end of which is connected by a conductor R' with the positive commu-

tator-brush K. I may note here that the conductor R' instead of leading to the positive commutator-brush K might lead to the conductor D or to the positive bus-bar A. The 5 said armature M³ is adapted to act as one member of a tripping device which also includes a finger H², located upon the free end of the movable conductor H. When the armature M³ is attracted by the electromagnet, 10 it is disengaged from the finger H², leaving the spring S, attached to the movable conductor H, free to act and automatically move the said conductor into engagement and electrical contact with a contact-piece or clip T, 15 which is located directly below the contact-piece or clip G, before mentioned, the contact-piece or clip T being connected by a conductor U with the conductor D.

Having thus described an illustrative embodiment of my invention, let it be assumed 20 that the current has risen above a predetermined fixed value on account of an overload or a short circuit or from any other cause. The electromagnet will then under this increased current attract its armature M³, which 25 will be withdrawn from the finger H² of the blade H, so as to release the same and permit the same to be moved by its spring S, so as to disengage it from the contact-piece or clip G 30 and engage it with the contact-piece or clip T. It may be here noted that the spring M², carrying the armature M³, is adjusted in tension so that the current normally flowing through the coil M will not attract the armature M³ sufficiently to release the movable conductor. The described movement of the 35 blade or conductor H breaks the equalizer connection through the contact-piece or clip G and short-circuits the series windings E 40 through the contact-piece or clip T. The effect of this is to convert the compound-wound machine virtually into a simple shunt-wound machine without breaking the main circuit of the same. The machine now being a simple shunt-wound machine has all the characteristics of the same.

It will be apparent to any one skilled in the art to which this invention relates that without departing from the principle of the invention the electromagnet may be connected 50 as a shunt to the main circuit from the brush O to the negative bus-bar C, as shown in dotted lines in Fig. 1. The electromagnet may also be connected in on the same side of the machine to which the equalizer connection is made. It will also be understood that a solenoid may be used instead of an electromagnet. It will also be understood that the polarity of the machine may be reversed—that 55 is, the brush K might be the negative brush and the brush O the positive—the polarity of the bus-bars at the same time being reversed.

In Fig. 2 of the drawings I have illustrated another embodiment of my invention, which 60 in this instance is designed to effect not only the short-circuiting of the series windings and the open-circuiting of the equalizer connection, but also the opening of the circuit through the series windings without breaking the main

connection, but also the opening of the circuit through the series windings, without breaking the main circuit. In this embodiment of my 70 invention I employ a positive bus-bar or conductor a, an equalizer bus-bar or conductor b, and a negative bus-bar or conductor c. The said positive bus-bar is connected by a conductor d to one end of the series windings e, 75 the other end of which is connected by a conductor f with a contact-piece or clip g, which is normally in electrical contact with a movable conductor h in the form of a wide copper blade which is hung upon a pivot h' in a fixed 80 bracket i, with which the blade is in electrical contact. The equalizer bus-bar or conductor b is connected by a conductor j with a contact-piece or clip k, which is also normally in electrical contact with the movable conductor 85 or blade h. The negative bus-bar or conductor c is connected by a conductor l with one end of the coil n of an electromagnet, which also comprises a yoke n', having legs n² and n³, of which the leg n² is encircled by the said 90 coil n, the opposite end of which is connected by a conductor l' with the negative commutator-brush o, which rides upon the commutator o'. The said brush o is connected by a conductor p with one end of the shunt- 95 windings q, the other end of which is connected by a conductor q' with the positive commutator-brush o², which is connected by a conductor r with the bracket i, before mentioned. To the leg n³ of the yoke n' I secure 100 a spring s, the lower end of which carries an armature t, which coacts with the leg n² of the yoke n'. The said armature t is normally engaged by a finger h², carried by and projecting from the free end of the movable conductor or blade h. A spiral spring u, connected with the said blade at one end, exerts a constant effort to draw it away from the contact pieces or clips k and g and into contact with a contact-piece or clip v, located on the side 110 of the blade h opposite to the contact-pieces or clips k and g and connected by a conductor w with the main or working line d. When the current rises above a predetermined fixed 115 value on account of an overload or short circuit or on account of any other cause, the electromagnet attracts the armature t sufficiently to overcome the spring s and to release the finger h², after which the spring u immediately acts to move the blade h away from the 120 contact-pieces or clips k and g toward the contact-piece or clip v, with which the blade is brought into electrical contact before it breaks electrical contact with the clip g, whereby the series windings e will be short-circuited and 125 then cut out of circuit without breaking the main or working circuit.

In Fig. 3 I have illustrated another embodiment of my invention, which in this instance is designed to effect not only the short- 130 circuiting of the series windings and the open-circuiting of the equalizer connection, but also the opening of the circuit through the series windings without breaking the main

circuit. This, however, is effected without carrying more than three wires from the dynamo to the switchboard on which the apparatus is usually mounted, while in Fig. 2 5 four wires are carried to the switchboard. In this embodiment of my invention I employ a positive bus-bar or conductor A', an equalizer bus-bar or conductor B', and a negative bus-bar or conductor C'. The said positive bus-bar is connected by a conductor W' to a contact-piece or clip Y', normally in contact with an auxiliary movable conductor or blade X'. The said contact-piece or clip Y' is also connected by a conductor U' with a contact-piece or clip T'. The movable conductor or blade X' is hung upon a pivot Q', in a fixed bracket Q', with which the blade is in electrical contact, and which in turn is connected by the conductor D' with one terminal of 10 the series windings E', the other terminal of the series windings E' being connected to the brush K'. The equalizer bus-bar or conductor B' is connected by a conductor F' with a contact-piece or clip G', which is normally in 15 electrical contact with a movable conductor or blade H'. The movable conductor or blade H' is hung on a pivot H' in a bracket I' and is in electrical contact with the same. The said bracket I' is connected by a conductor J' to the brush K'. The negative bus-bar or conductor C' is connected by a conductor L' with one end of the coil M' of an electromagnet, which also comprises a yoke M', having 20 legs m² m³, of which the leg m² is encircled by the said coil M', the opposite end of which is connected by a conductor N' with the negative commutator-brush O', which rides upon the commutator P'. The said brush O' is connected by a conductor R' with one end of 25 the shunt-windings R', the other end of which is connected by a conductor R' with the positive commutator-brush K'. To the leg m³ of the yoke M', I secure a spring M', the lower end of which carries an armature M', which 30 coacts with the leg m² of the yoke M'. The said armature M' is normally engaged by a finger H', carried by and projecting from the free end of the movable conductor or blade H'. A spiral spring S', connected with the 35 said blade at one end, exerts a constant effort to draw it away from the contact-piece or clip G' and into contact with the contact-piece or clip T', located on the side of the blade H' opposite to the contact-piece or clip G'. The movable conductor or blade H' has 40 on its other extremity a non-conducting piece H', which engages a lip V' on the auxiliary blade X' and holds the said auxiliary blade X' in contact with the contact-piece or clip Y' against the pressure of spring S'. S' is a 45 small stop for preventing too great a movement of the auxiliary blade X'. When the current rises above a predetermined fixed value on account of an overload or short circuit or on account of any other cause, the electromagnet attracts the armature M' sufficiently to overcome the spring M' and to

release the finger H', after which the spring S immediately acts to move the blade H' away from the contact-piece or clip G' and toward the contact-piece or clip T', with which the blade is brought into electrical contact. At the same time by the movement of the blade H' the auxiliary blade X' is released, and the spring S' immediately acts 75 and breaks the contact of the blade X' with the contact-piece or clip Y'. This, however, is not effected until the blade H' makes contact with the contact-piece or clip T', whereby the connection to the equalizer bus-bar 80 will be broken and the series windings E' short-circuited and then cut out of circuit without breaking the main or working circuit.

In each of the embodiments of my invention chosen for illustration I have shown apparatus designed for use in conjunction with several machines operated in parallel, it being only necessary to conceive the conductors A, B, and C in Fig. 1, a, b, and c in Fig. 2, and A', B', and C' in Fig. 3 as extended and 85 the apparatus and connections shown in the respective figures duplicated; but my invention is also applicable to single dynamos, in which case the equalizer bus-bar or conductor B, the conductor F, and the clip G in Fig. 95 1, the equalizer bus-bar or conductor b', the conductor j', and the clip k' in Fig. 2, and the equalizer bus-bar or conductor B', the conductor F', and the clip G' in Fig. 2 will be dispensed with.

Fig. 4 of the drawings shows the connection in parallel of two machines like that shown in Fig. 1, while Fig. 5 of the drawings, which is also based upon Fig. 1, shows the application of my invention to a single dynamo.

In view of the modifications suggested and of others which may obviously be made I would have it understood that I do not limit myself to the exact construction herein shown 110 and described, but hold myself at liberty to make such changes as fairly fall within the spirit and scope of my invention.

Having fully described my invention, what I claim as new, and desire to secure by Letters 115 Patent, is—

1. An automatic apparatus for short-circuiting the series windings of a compound-wound dynamo, the said apparatus comprising a device electrically operated for short-circuiting the series windings of the dynamo in case of an overload or a short-circuit on the line, and requiring manual operation for again throwing the current of the dynamo onto the line.

2. An automatic apparatus for short-circuiting the series windings of a compound-wound dynamo the said apparatus comprising an electrically-operated device, and means automatically actuated by the said device for opening the equalizer connection when two or more of such machines are connected for operation in parallel.

3. An automatic apparatus for short-cir-

- 4
- cuiting the series windings of a compound-wound dynamo comprising an electrically-operated device, and means automatically actuated by the said device for opening the equalizer connection when two or more of such machines are connected for operation in parallel, and also for automatically cutting out the series windings without breaking the main or working circuit.
- 5 4. An automatic apparatus for short-circuiting the series windings of a compound-wound dynamo, the said apparatus including an electromagnetic device, a movable conductor constantly maintained in its normal position by means of the said electromagnetic device, and automatically moved when released thereby, and a contact-piece located in position for being electrically engaged by the said movable conductor when the same is released, and connected to one terminal of the series windings of the machine, the other terminal of which is so connected that the said movable conductor when released will short-circuit the series windings.
- 10 5. An automatic apparatus for short-circuiting the series windings of a compound-wound dynamo and opening the equalizer connection thereof, the said apparatus comprising an electromagnetic device, a movable conductor constantly maintained in its normal position by means of the said electromagnetic device, and automatically moved when released thereby, a contact-piece or clip connected with the equalizer-conductor or bus-bar and normally in electrical contact with the said movable conductor, and a contact-piece or clip which is engaged by the said conductor when the same is moved after its release by the electromagnetic device, and which is connected with one terminal of the series windings, the other terminal of which is so connected that the said movable conductor when released, will short-circuit the series windings.
- 15 6. An automatic apparatus for short-circuiting the series windings of a compound-wound dynamo, and opening the equalizer connection thereof and cutting out the series windings without breaking the main or working circuit, the said apparatus comprising an electromagnetic device, a movable conductor constantly maintained in its normal position by means of the said electromagnetic device and automatically moved when released thereby, a contact-piece or clip connected with the equalizing-conductor or bus-bar and normally in electrical contact with the said movable conductor, a contact-piece or clip which is engaged by and in electric contact with the said conductor when the same is moved after it is released by the electromagnetic device, said conductor being connected with one terminal of the series windings, and a contact-piece or clip normally in electrical contact with the said movable conductor, and connected with the other terminal of the series windings, and disconnected from the mov-

able conductor when the same is moved after its release, but not before it comes in contact with the contact-piece or clip connected with the main or working circuit.

7. An automatic apparatus for short-circuiting the series windings of a compound-wound dynamo, the said apparatus including an electromagnetic device, a movable conductor constantly maintained in its normal position by the said electromagnetic device, and automatically moved when released thereby, and in electrical connection with that brush of the dynamo which is directly connected to the series windings, and a contact-piece located in position for being electrically engaged by the said movable conductor when the same is released and connected to one terminal of the series windings of the machine, the other terminal being connected to the said brush.

8. An automatic apparatus for short-circuiting the series windings of a compound-wound dynamo, and for opening the equalizer connection when two or more machines are connected for operation in parallel, the said apparatus including an electromagnetic device, a movable conductor constantly maintained in its normal position by means of the said electromagnetic device, automatically moved when released thereby and electrically connected with one brush of the machine, a contact-piece or clip connected with the equalizer conductor or bus-bar and normally in electrical contact with the said movable conductor, a contact-piece located in position for being electrically engaged by the said movable conductor when the same is released, and connected to one terminal of the series windings of the machine, the other terminal of which is connected with the same brush.

9. An automatic apparatus for short-circuiting the series windings of a compound-wound dynamo, the said apparatus comprising an electromagnetic device, a movable conductor consisting of a pivotally-mounted blade adapted at one end to be engaged with and normally supported through the agency of the electromagnetic device, and to be automatically moved when released thereby, and one or more contact-pieces or clips located adjacent to the said bar for coaction therewith, as and for the purpose set forth.

10. An automatic device for short-circuiting the series windings of a compound-wound dynamo and opening the equalizer connection thereof and cutting out the series windings without breaking the main or working circuit, the said apparatus comprising an electromagnetic device, a movable conductor constantly maintained in its normal position by means of the said electromagnetic device, and automatically moved when released thereby, the said conductor connected to one terminal of the series windings, a contact-piece or clip connected with the equalizer conductor or bus-bar and normally in electrical contact with the said movable conductor, a con-

- tact-piece or clip which is engaged by and in electrical contact with the said conductor when the same is moved after it is released by the electromagnetic device, and connected to a contact-piece or clip normally in electrical contact with an auxiliary movable conductor which is constantly maintained in its normal position by means of the main movable conductor, and automatically moved when released thereby, said auxiliary conductor being connected to one terminal of the series windings, the other terminal of which is so connected that when the main movable conductor is released and the auxiliary movable conductor is released, the series windings will be short-circuited and then cut out of circuit. 15
